UNITED STATES PATENT OFFICE.

EDWIN W. BULLARD, OF WHITNEYVILLE, CONNECTICUT, ASSIGNOR TO WINCHESTER REPEATING ARMS CO., OF NEW HAVEN, CONNECTICUT, A CORPORATION.

RATCHET MECHANISM.

1,388,919.

Specification of Letters Patent. Patented Aug. 30, 1921.

Application filed August 13, 1920. Serial No. 403,197.

To all whom it may concern:

Be it known that I, EDWIN W. BULLARD, a citizen of the United States, residing at Whitneyville, in the county of New Haven 5 and State of Connecticut, have invented a new and useful Improvement in Ratchet Mechanisms; and I do hereby declare the following, when taken in connection with the accompanying drawings, and the characters of reference marked thereon, to be a full, clear, and exact description of the same, and which said drawings constitute part of this application, and represent, in—

Figure 1, a plan view of my improved 15 ratchet-mechanism with its crank-arm broken away.

Fig. 2, a corresponding view in side elevation.

Fig. 3, a view in longitudinal section on 20 the line 3—3 of Fig. 2.

Fig. 4, a view in vertical section on line 4—4 of Fig. 2.

Fig. 5, a detached plan view of the ratchet.

Fig. 6, a broken side view thereof.

Fig. 7, a perspective view of the washer provided for the suspension of the ratchet in the housing of the mechanism.

Fig. 8, a detached plan view of one of the 30 floating, spring-actuated pawls.

Fig. 9, a side view thereof.

Fig. 10, a detached view of one of the pawl-springs.

Fig. 11, an edge view thereof.

35 My invention relates to an improved ratchet-mechanism, the object being to produce a ratchet-mechanism constructed with particular reference to simplicity of construction, fewness of parts, convenience of 40 operation and ruggedness in use.

With these ends in view my invention consists in a ratchet-mechanism having a housing, a ratchet, and two spring-actuated complementary floating-pawls for co-action 45 with the ratchet. My invention further consists in a ratchet-mechanism having certain details of construction and combination of parts as will be hereinafter described and pointed out in the claims.

50 In carrying out my invention, I employ two complementary floating pawls 12 respectively positioned in longitudinally arranged oblong assembly-openings 13 formed in the opposite faces of a ratchet-housing 14 receiving the ratchet 15 with the teeth of which the

said pawls co-act. I have characterized the pawls 12 as "floating" pawls for the reason that instead of swinging on fixed pivots or having constrained longitudinal movement, they are free to rock as well as to slide longitudinally, being yieldingly held in any of their positions by means of flat-sheet-metal pawl springs 16 located within the pawl-chamber 17 of the housing as clearly shown in Fig. 3.

60 Each of the pawls is formed upon its inner face with a blunt nose 18 for co-action with the teeth of the ratchet 15, at its outer end with a tongue 19 sliding upon the adjacent portion of the exterior surface of the 70 housing and at its inner end with a stabilizing extension 20 terminating in transversely arranged retaining-lugs 21 which latter prevent the pawl from being inadvertently pushed forward out of its opening 13. The 75 pawls are also formed upon their projecting outer faces with serrations 22, whereby they are engaged by the fingers and pushed inwardly or longitudinally as required. The pawls are also provided in their outer faces with transverse positioning-notches 23 and 80 24 co-acting according to their longitudinal positions with transversely arranged combined fulcrum and abutment shoulder 25 formed upon the inner walls of the housing 85 in positions coincident with the inner ends of the assembling-openings 13 therein, and therefore opposite each other.

85 In Fig. 3 of the drawings, the upper pawl is shown in its retired position in which its 90 nose 18 is cleared from the ratchet and in which its notch 23 has received its complementary shoulder 25, the pawl being yieldingly held in this retired position by its spring 16. In the same figure, the lower pawl is shown with its nose 18 engaged with the ratchet and its notch 24 engaged with its complementary fulcrum and abutment shoulder 25, whereby the pawl is yieldingly held in its active position. From the positions in which the respective pawls are 95 shown in Fig. 3, they are readily moved by first unlocking them by inward pressure and then shoving them longitudinally in one direction or the other as may be desired. When 100 the ratchet is being operated, the active pawl will have a rocking motion upon its complementary shoulder while the inactive pawl will remain at rest.

105 As shown, the ratchet 15 is suspended in 110

the housing by means of a screw 26 mounted in a suspension-washer 27 fitting into a recess 28 in the upper end of the housing.

I claim:

- 5 1. A ratchet-mechanism having a housing formed with complementary assembling-openings, a ratchet located in the said housing, and two complementary spring-actuated floating pawls entering the respective assembling-openings and each having rocking and longitudinal movement with respect to the ratchet with which they co-act.
- 10 2. A ratchet-mechanism having a housing formed with a pawl-chamber and two oppositely located assembling-openings leading thereinto, a ratchet located in the said housing, two complementary spring-actuated, floating pawls located in the said pawl-chamber and entering the respective assembling-20 openings and having yielding, rocking and longitudinal movement with respect to the ratchet and engaging in different positions with the housing.
- 15 3. A ratchet-mechanism having a housing formed with a pawl-chamber the side walls of which have assembling-openings, a ratchet in the said housing, two complementary, floating, spring-actuated pawls located in the said chamber and respectively entering the

said openings and having longitudinal and 30 rocking movement therein, and combined fulcrum and abutment shoulders located within the housing at the inner ends of the said openings and co-acting with the said pawls in their two positions of longitudinal 35 adjustment.

4. A ratchet-mechanism having a housing formed with a pawl-chamber and two oppositely located assembling-openings, a ratchet located in the said housing, and two 40 complementary, floating, spring-actuated pawls located in the said chamber and entering the respective openings, the forward ends of the said pawls extending through the openings for co-action with the exterior of 45 the housing and their rear ends co-acting with the interior thereof and the outer faces of the pawls being formed with transverse notches co-acting with transverse shoulders located within the housing at the inner ends 50 of the said openings.

In testimony whereof, I have signed this specification in the presence of two subscribing witnesses.

EDWIN W. BULLARD.
